UNITED STATES PATENT OFFICE.

ANTONIO CAMPANARO, OF TRENTON, NEW JERSEY.

MEANS FOR PROTECTING VESSELS FROM PROJECTILES.

1,249,323.

Specification of Letters Patent. Patented Dec. 11, 1917.

Application filed July 26, 1917. Serial No. 182,951.

To all whom it may concern:

Be it known that I, ANTONIO CAMPANARO, a citizen of the United States, and a resident of Trenton, county of Mercer, State 5 of New Jersey, have invented certain new and useful Improvements in Means for Protecting Vessels from Projectiles, of which the following is a specification.

The present invention relates to improvements in means for protecting vessels from projectiles, being adapted to be utilized to ward off torpedoes or if arranged to extend over the deck to prevent falling projectiles or bombs from striking the vessel.

15 In the accompanying drawings, the invention is shown embodied in a form adapted to protect a vessel from torpedoes and in such drawings,

Figure 1 is a side elevation of a vessel 20 having one embodiment of the invention applied thereto;

Fig. 2 is a transverse vertical sectional view;

Fig. 3 is a face view, on an enlarged scale, 25 of the connection between the supporting frame and guard net;

Fig. 4 is an elevation of a portion of the net;

Fig. 5 is a sectional view of the parts 30 shown in Fig. 4;

Fig. 6 is a detail plan view;

Fig. 7 is an end elevation of one of the supporting frames and nets.

Fig. 8 illustrates in side elevation and 35 front view a device which may be employed for adjusting the lock by which the guard is normally maintained in position for use.

Referring to the drawings, it will be seen 40 that the invention comprises a plurality of guards or shields adapted to be supported from a vessel and to extend throughout the length thereof. Preferably each of these guards or shields comprises a net-like body which is supported from a frame adapted to 45 be detachably attached to the vessel and which can be readily placed in position or removed, as desired. As shown, each frame comprises two parallel bars A which are provided at one end with means for securing 50 them to the deck or sides of a vessel and to which, adjacent the opposite or free ends thereof, the guard net or shield proper is connected by a suitable hinge-like joint. The bars A are preferably made in the form

shown in Fig. 2, so that when placed over 55 the sides of a vessel they are separated some distance therefrom. Said bars are connected by suitable tie rods B on the outer ends of which may be mounted rollers C which will contact with the sides or deck of the 60 vessel as the frames are moved to and from position, thus assisting in such movement and preventing injury to the parts. Said rods B may be surrounded by spacing thimbles or sleeves B', as shown in Fig. 3. 65

The side frame bars A may be attached to the vessel in any suitable manner. As shown, each of them is provided near one end with a suitable opening adapted to receive a staple-like member D rising from the 70 deck of the vessel and a rod or bar E is passed through said staples above the bars A and suitably locked in position to hold the parts in the desired relation to the vessel. 75

In the embodiment of the invention illustrated, one of the longitudinal members F of the marginal frame of the guard or net proper is mounted in suitable bearings on the supporting bars A and a coil spring G 80 is placed around this frame member, one end of said spring being connected with the bar A and the other with a side member of the net frame so that the net constantly tends to assume a position at a relatively wide 85 angle to the bars A. Cables H connected with the frame of the net, passing over suitable guide pulleys on the bars A and extending to the deck of the vessel are provided for moving the net into a position 90 parallel to the plane of the bars A and placing the springs G under tension.

To the deck of the vessel are hinged guide tubes I through which the cables H extend, 95 said cables being provided at their free ends with stops H' of such size that they cannot pass through the tubes I. The hinges h by which said cable tubes are connected to the deck of the vessel are arranged at one side thereof and at the other side each tube is provided with a hasp i adapted to engage a suitable staple rising from the deck so that normally the portions of the cables that extend over the vessel's deck are concealed and protected. When it is desired to draw the net 105 into the position indicated in full lines in the drawings, the proper tubes I are disconnected from the deck staples and turned

about their hinges *h* exposing the cables and permitting them to be readily manipulated, as required.

To retain the nets in operative position, a suitable locking means is provided. As shown, this consists of a hook or latch member *K* which is mounted on one of the tie rods *B* of the supporting frame and is adapted to engage the upper marginal frame 10 of the net and be held in engagement therewith by the pull or force exerted by the springs *G* which constantly tend to swing the net outwardly about its hinge-like connection with said frame.

Preferably the members forming the body of the net or guard are provided with resilient tubular coverings *L* which will act to more or less cushion the blow of a projectile striking the net. The various parts 20 are so proportioned that the openings or meshes in the net are not large enough to permit the passage of a projectile and it will be seen that with the parts arranged as shown in Figs. 1 and 2, when the net is struck, the slight rearward movement of the free end thereof will disengage the hook or latch *K*, which will fall by gravity, and the springs *G* will instantly act to force the net outwardly into the position indicated in dotted lines, carrying the projectile with it and preventing its striking the body of the vessel even should it be able to penetrate the net. In order to enable the net to be readily restored to its operative position, 30 it is necessary to provide means for limiting the outward swinging movement thereof. This is accomplished in the embodiment of the invention illustrated by providing guards *M* on the supporting frame bars *A*, each of said guards having a stop member *M'* that extends into the path of a member of the net and prevents the latter from falling below the plane of its pivotal axis, when the parts are arranged as shown in the 40 drawings. With this arrangement an excessive amount of power is not required to draw in the cables *H* to restore the net to the position represented in full lines.

If the device is employed as shown for 50 protecting vessels from a torpedo attack, the parts are so proportioned that normally the upper edges of the nets are at or about the water line and extend to below the plane of the keel of the vessel. As the hooks or 55 latches *K* may be submerged, an implement, such as that shown in Fig. 8, may be employed to raise such latches into position to engage the net after the cables have been manipulated to restore it to normal position. This implement comprises two similar pivotally connected members *N*, the 60 lower ends of which are provided with laterally deflected prongs *O*. With such an implement the hook *K* may be readily 65 grasped and caused to extend through an

opening *P* formed by notches in the inner edges of the members *N* and when so engaged can be easily lifted in position to engage the net after which the tongue-like implement can be easily disengaged therefrom. 70

It is believed that the operation and advantages of the invention will be readily understood and appreciated. It will be seen that the frame bars *A* may be quickly placed in position and securely connected 75 with the vessel as the frames need not be excessively large the number thereof depending upon the length of the vessel or the portion thereof which it is desired to protect. If desired, supplemental braces *Q* may 80 be interposed between the walls of the vessel and the frame members *A*.

Having described the invention what is claimed is:—

1. The combination with a vessel, of a 85 frame connected at one end to the vessel, a guard net or shield connected with the frame by a hinge-like joint permitting it to swing outwardly away from the vessel, a spring acting to swing the net outwardly, and means for normally holding the net in 90 position to maintain the spring under tension, adapted to be automatically released when the net is struck by a projectile.

2. The combination with a vessel, of a 95 frame having its upper end connected to the vessel and extending over the side thereof to below the water line, a guard net or shield having its lower end connected with the frame by a hinge-like joint, a spring interposed between the frame and net and acting 100 to turn the latter about its connection with the frame, means for turning the net into a substantially vertical position against the action of the spring, and means for holding the net in such upright position adapted to 105 be automatically released when the net is struck by a projectile.

3. The combination with a vessel, of a 110 frame, including two parallel members attached at their upper ends to the vessel and extending over the side thereof to below the waterline, and rods connecting and bracing said members, a guard net or shield having its lower end connected with said frame by 115 means permitting it to swing about a substantially horizontal axis, coiled springs between the frame and net acting to swing the latter outward and downward, means for limiting the downward movement of the net, and means for holding the net in a substantially upright position against the action of the springs and to be automatically released when the net is struck by a projectile.

4. The combination with a vessel, of a 120 frame connected at one end to the vessel, a guard net or shield connected with the frame at one end by a hinge-like joint permitting it to swing away from the vessel, 125

a spring acting to swing the net outwardly, a cable connected with the net and guided by the frame for moving the net in opposition to the spring, and means for holding the net in position to maintain the spring under tension adapted to be automatically released when the net is struck by a projectile.

5. The combination with a vessel, of two substantially parallel bars each attached at one end to the vessel, a guard net or shield having one of its frame members mounted in bearings on said bars whereby the net may swing away from the bars outward of the vessel, coiled springs attached to said bars 10 and frame of the net and acting to swing the net outward from the vessel, a stop on each bar for limiting the outward swing of the net, means for turning the net in opposition to the springs, and means for holding the net in position to maintain the springs under tension and adapted to be automatically released when the net is struck by a projectile.

6. A projectile guard for vessels comprising a metal net, supporting bars having hinge-like connections with the net, adjacent one end, and adapted to have their other ends secured to a vessel, a spring acting to turn the net about its connection with the supporting bars away from the latter, means for moving the net toward the bars, and means for holding the net in position to maintain 25

the spring under tension adapted to be automatically released when the net is struck by a projectile.

35

7. A projectile guard for vessels comprising a metal net having more or less of its members provided with resilient coverings, supports hinged adjacent one end to said net and adapted to have their other ends secured to a vessel, a spring acting to swing the net away from said supports, and means for holding the net in position to maintain the spring under tension adapted to be automatically released when the net is struck by a projectile.

40

8. A projectile guard for vessels comprising a frame formed of substantially parallel bars adapted to be attached at one end to a vessel and connected by suitable tie bars or rods, rollers attached to said frame for contacting with the vessel as the frame is moved to and from operative position, a net hinged at one edge to the frame, a spring acting to swing the net outwardly from the supporting frame, means for moving the net in opposition to the spring, and means for holding the net in position to maintain the spring under tension adapted to be automatically released when the net is struck by a projectile.
